RESONANT CHAMBER FOR MICROPHONES

Frank Massa, Cleveland Heights, Ohio

Application August 24, 1945, Serial No. 612,451

6 Claims. (Cl. 181—0.5)

1

My invention is concerned with microphones, and, more particularly, with means for varying the frequency response characteristic of a microphone.

In certain applications, of which a vacuum tube hearing aid is an example, it is desirable to provide adjustment for the frequency response characteristic of the system in order to permit the user of the instrument to adjust the characteristic to suit his needs best. Heretofore, the means employed for permitting an individual to obtain the frequency response best suited for his individual requirements have been to provide a number of receivers having different response characteristics and also variable electric circuit elements to cause changes in the response characteristic of the amplifier.

In my invention, I provide an inexpensive means for varying the response characteristic of the microphone which, besides being simpler, cheaper and more flexible than the heretofore used methods, possesses the additional advantage that the signal to noise ratio of the system is improved because I am able to realize an absolute increase in the sensitivity of the microphone over desired portions of the audio-frequency range, and thereby increase the electrical signal at the amplifier input for a given sound intensity, which serves to reduce the audible background noise resulting from thermal noise or microphonic agitation of the early amplifier stages.

The basic principle of my invention is to mount the microphone within an enclosure which communicates with the outside atmosphere through an opening; then, by varying the size of the opening through which sound is admitted to the enclosure or by varying the volume of the enclosure, I am able to increase the sensitivity of the microphone over different portions of the audio-frequency range determined by the size of opening and size of volume of enclosure which are employed.

In one embodiment of my invention, for an improved type of hearing aid unit, I mount the conventional hearing air microphone within a sealed-off portion of the amplifier housing and provide an opening along the side of the housing over which may be moved an adjustable shutter to vary the amount of opening exposed. By this means, the user of the instrument may adjust the tone quality of his device to suit his needs best.

As generally worn, a hearing aid instrument is placed underneath the outer garments, and for the conventional structure employing a microphone with an open grill, the clothing seals off the openings on the front of the microphone housing, thereby resulting in considerable attenuation of the higher audio frequencies. In one adaptation of my invention for hearing aid use, I place the adjustable opening along the edge of

2

the amplifier housing so that when the housing is placed beneath an article of clothing, the open edge will be more generally unobstructed to the sound approaching the unit.

5 An object of my invention is to vary the frequency response characteristic of a microphone by simple external adjustable mechanisms.

Another object of my invention is to increase the sensitivity of a microphone over any portion 10 of a desired range of audio frequencies.

Still another object of my invention is to vary the response characteristic of a microphone by mounting it within an enclosure which communicates to the free atmosphere through an 15 adjustable opening.

A further object of my invention is to vary the response characteristic of a microphone by mounting the microphone within an enclosure of adjustable volume which communicates to the free atmosphere through an orifice.

A still further object of my invention is to provide simple tone adjustment means in a hearing aid instrument by mounting a microphone within an enclosed portion of the hearing aid instrument 25 and providing an adjustable opening for communicating between the enclosure and the outside atmosphere.

Another object of my invention is to provide a hearing aid device whose sensitivity over any 30 portion of a desired range of audio frequencies may be enhanced to "fit" the hearing aid to the user's particular requirement.

It is also an object of my invention to provide a hearing aid device whose sensitivity over a portion 35 of its frequency range may be changed from time to time as the wearer's hearing changes, thereby saving the wearer from purchasing a number of the devices.

Still a further object of my invention is to provide a hearing aid device which may be manufactured as a standard item and which the salesman or the wearer himself may easily adjust to compensate for the wearer's particular hearing defect.

45 Other objects and advantages of my invention will become evident by reading the specifications which follow. The novel features that I consider characteristic of my invention are set forth 50 with particularity in the appended claims. The invention, itself, however, both as to its organization and method of operation, as well as advantages thereof, will best be understood from the following description of several embodiments 55 thereof, when read in connection with the accompanying drawings, in which—

Fig. 1 shows a microphone mounted within an enclosure which is provided with an adjustable opening for communicating from the enclosure to 60 the outer atmosphere.

Fig. 2 is a section taken along the line 2—2 of Fig. 1.

Fig. 3 shows a partially cut-away view of another arrangement for realizing the principle of my invention in which a microphone is mounted within an enclosure of adjustable volume which communicates to the outer atmosphere through a fixed orifice.

Fig. 4 is a section taken along the line 4—4 of Fig. 3.

Fig. 5 is a schematic view of a hearing aid instrument with the front cover removed and showing the location of the microphone and a variable shutter mechanism for adjusting the opening which communicates from the outer atmosphere to the enclosure in which the microphone is mounted.

Fig. 6 is a side view of the hearing aid unit indicated in Fig. 5 with the front cover attached.

Fig. 7 is a graph showing the changes in the frequency response characteristic produced by varying the position of the shutter in either Fig. 1 or Fig. 5.

Referring more specifically to Fig. 1 and to Fig. 2, the reference character 1 indicates a conventional small pressure microphone as generally employed in hearing aid instruments. The microphone is resiliently mounted on a back plate 2 by means of flexible rubber pads 3, which may be cemented or otherwise affixed to the back plate 2 and to the housing of the microphone 1. The back plate 2 is attached to a cup-shaped housing 4 by means of the screws 5. Into the flat or bottom face of the housing 4 is cut a semi-circular opening 6 which is shown dotted in Fig. 1. To the flat face of the housing 4 is attached a rotatable disc 7 which is held in place by the rivet 8. Into the disc 7 is cut a semi-circular opening 9 which may be brought into alignment with the opening 6. As the disc 7 is rotated about the rivet 8 with respect to the housing 4, the amount of opening which is exposed through the housing 4 may be controlled. As the amount of opening is varied, the microphone 1 will find itself effectively inside a Helmholtz resonator whose resonant frequency gets higher and higher as the exposed opening is made larger and larger. The effect of this situation on the acoustic response of the microphone is to increase its sensitivity over the region of resonance. Since this region is adjustable by the mechanical position of the shutter 7, the microphone response will correspondingly change in accordance with the position of shutter 7. Some actual experimental data showing the measured changes in the response of a microphone under certain conditions of enclosed volume and orifice area will be presented in connection with Fig. 7. Although it is not indicated in Figs. 1 and 2, I may add a sheet of sound absorbing material such as felt over the opening 6 if I wish to damp the acoustical resonance and reduce the magnitude of the increase in the peak sensitivity of the microphone in the resonance frequency range determined by the microphone enclosure volume and the size of the adjustable opening.

In Fig. 3 and Fig. 4 is shown an alternative arrangement for producing the same effect as obtained in the system of Figs. 1 and 2. The microphone 1 is mounted on flexible rubber pads 3 in the same way as described in connection with Fig. 2. The microphone is attached to the back plate 10 which, in turn, is secured to the substantially cup-shaped housing 11 by means of the screws 12. Through the housing 11 is a

screen-covered opening 13 which provides communication from the outer atmosphere to the volume enclosed by the housing 11 and back plate 10. An adjustable end plate 14 which may be moved as high as the position 14' completes the assembly. The end plate 14 slidably fits within the housing so that frictional forces hold it in any place to which it is moved, or alternatively, set screws or a notch and spring arrangement somewhat similar to the notch and spring device shown in Fig. 5 may be used to hold the end plate 14 within the housing. As the end plate 14 is moved within the housing, the volume of the enclosure will be varied, which will result in a variation in the frequency response characteristic of the microphone in a manner similar to that produced by varying the shutter opening in Fig. 1, and, although it is not illustrated, the device shown in Figs. 3 and 4 may have its opening 13 variable in size as has been described in Figs. 1 and 2.

Figs. 5 and 6 show the schematic embodiment of my invention in connection with a vacuum tube hearing aid instrument. The housing of the instrument consists of a case 15 and a front cover 16 which is shown in Fig. 6 but which is removed in Fig. 5. A ridge 31 is provided to divide the housing 15 into two portions. A mating ridge, not shown, is provided in the cover piece 16 so that when the cover is assembled in place, the housing 15 will be divided into two separate compartments, for example, a top compartment and a bottom compartment. The microphone 1 is mounted in the top compartment, as indicated in Fig. 5. The reference character 17 illustrates a volume control which may be located, as shown, along the top edge of the housing. A small ridge 18 is provided in the housing 15 so that a guide track 19 will be provided for the shutter 20. A similar ridge and guide for the shutter 20 is also provided along the inside edge of the cover piece 16 so that at final assembly the shutter 20 is effectively secured between two parallel guides. A number of notches 21 are provided, as shown on the back of the shutter 20, and a spring 22 which is riveted to the wall of the ridge 31 acts as a locking device to hold the shutter in any desired notched position. A rectangular opening 23 exists along one edge of the housing 15, as shown. A smaller, similar rectangular opening 24 is provided along the top edge of the housing 15. The size of the opening 24 is made such that when the shutter 20 is raised to close completely the opening 23, the opening 24 will provide increased microphone sensitivity at the lowest frequency desired in the hearing aid instrument. As the shutter 20 is lowered successively to cause the opening 23 to become larger and larger, the high-frequency sensitivity of the microphone will continue to increase more and more, thereby resulting in a variable tone quality which can be set at the will of the user. Although a manual adjustment for the shutter 20 has been illustrated, I may also provide other means for adjusting the position of the shutter 20 that would necessitate the use of special tools such as, for example, a locking set screw mounted into the housing 15 and adjustable for providing pressure against the shutter 20 to hold it in a fixed position. With such an alternative means for setting the size of the opening 23, the adjustment may be made by a skilled technician to best "fit" the individual's hearing loss characteristic. This adjustment may be repeated from time to time whenever the in-

dividual wishes to be "refitted." The cover piece 16 is made without any openings whatsoever. The only communication between the microphone and the outer atmosphere is through the side openings 23 and 24. This construction was chosen so that when the hearing aid instrument is worn underneath a coat or other garment, there will be less obstruction than would be the case were the openings kept on either the front or rear surface of the instrument. Reference characters 25, 26, 27, and 28 are schematic representations of circuit elements such as vacuum tubes or resistors that may form the amplifier circuit of the hearing aid instrument. Electrical connection may be established from the upper compartment of Fig. 5 to the lower compartment of Fig. 5 through suitable terminals which may be provided through the wall 31. In the lower compartment of Fig. 5, the reference characters 29 and 30 are schematic representations of other components of the electronic device such as, for example, the batteries which operate the instrument. These batteries may be mounted on spring clips, not shown, and a suitable opening, not shown, may be provided on the rear of housing 15 to permit ease in their replacement.

Fig. 7 shows the measured response characteristic of a small pressure microphone mounted inside an enclosure having a volume of $1\frac{1}{2}$ cubic inches. A communicating slit $\frac{3}{8}$ " wide was provided along one side of the housing. Curve A shows the measured response characteristic of the microphone in free space. Curve B shows the response of the microphone when mounted in the enclosure with the slit opening adjusted to a length of approximately $\frac{1}{4}$ inch. Curve C shows the measured characteristic when the slit opening was increased to approximately one-half inch. Curve D shows the characteristic when the slit opening was increased to approximately one inch, and curve E shows the characteristic measured with the slit opening approximately $1\frac{3}{4}$ inches long. In each case, there is an appreciable increase in the absolute sensitivity of the microphone over certain frequency regions, and the wide range of frequency over which the system is adjustable by the simple variable opening described will permit a wide choice of tone variations in a single instrument to permit easy tailoring of the acoustic characteristic to best fit the hearing loss of any individual. The response curves shown in Fig. 7 were taken without any acoustic damping material placed over the adjustable opening of the microphone enclosure. If acoustic damping material were placed over the opening, as previously mentioned, the tops of the peaks of the various curves shown in Fig. 7 would be "rounded off" to result in less gain in the absolute peak sensitivities at the various frequencies.

The use of this invention will provide great flexibility in tone control setting in a hearing aid instrument and because of the fact that the absolute sensitivity of the microphone is actually increased by my invention, an added advantage results over other means of electrical compensation in that the signal to noise ratio of the instrument is improved.

Although I have chosen only a few specific examples to illustrate the basic principles of my invention, it will be obvious to those skilled in the art that numerous departures may be made from the details shown, and I, therefore, desire that my invention shall not be limited except insofar as is made necessary by the prior art and by the spirit of the appended claims.

I claim as my invention:

1. In an electronic hearing aid system of the wearable type a thin housing structure comprising a walled enclosure of predetermined volume having an orifice in a wall thereof, said enclosure defining an acoustic resonant system, the cube root of the magnitude of the unoccupied portion of the volume within said enclosure being less than $\frac{1}{4}$ wavelength of the resonant frequency of said enclosure in the range 800 cycles per second to 2500 cycles per second, a pressure-actuated microphone mounted within said enclosure, and adjustable shutter means associated with said housing for varying the size of said orifice whereby the sensitivity of the microphone may be increased over predetermined portions of the frequency region 800 cycles per second to 2500 cycles per second.
2. The invention set forth in claim 1, further characterized in that said orifice is placed along one edge of said thin housing and said associated mechanical means for varying the size of said orifice includes a slidable wall portion attached to said housing, and means for selectively holding said slidable wall portion in any one of a plurality of positions.
3. In combination, a pressure-actuated microphone suspended within a walled enclosure of predetermined volume having an orifice in a wall thereof, said enclosure defining an acoustic resonant system, the cube root of the magnitude of the unoccupied portion of the volume within said enclosure being less than $\frac{1}{4}$ wavelength of the resonant frequency of said enclosure in the range 800 cycles per second to 2500 cycles per second, the surface area of at least one wall of said enclosure exposed to said microphone being variable.
4. The invention set forth in claim 3, further characterized in that one wall of said enclosure is movable with respect to the other walls of said enclosure whereby the volume within which said microphone is suspended may be varied.
5. The invention set forth in claim 3 further characterized in that adjustable shutter means is associated with said enclosure and is arranged to permit the closing off of a portion of said orifice.
6. The invention described in claim 3, characterized in that acoustic damping material is provided over said orifice.

FRANK MASSA.
